CARBURETOR

Johann Lichtenstein, Levallois-Perret, France, assignor to Societe Generale des Carburateurs Zenith, Levallois-Perret, France, a corporation of Switzerland

Application February 5, 1936, Serial No. 62,499
In Belgium February 8, 1935

3 Claims. (Cl. 261—50)

The present application relates to improvements in carburetors for internal combustion motors, of the type described in Belgian Patent 406,646, of December 5, 1934, in the name of 5 Societe Generale des Carburateurs Zenith, for improvements in Carburetors.

In said Belgian patent, there is described a carburetor comprising a mixture passage having an air inlet and a mixture outlet connected to 10 the motor, a throttle controlling the effective cross section of said passage, and a fuel outlet discharging into said passage posterior to the throttle. The carburetor is characterized essentially by a movable control member which 15 controls the pressure at which liquid fuel is supplied to the fuel nozzle, the position of said control member being a function of the absolute pressure obtaining in the mixing chamber of the carburetor posterior to the throttle and preferably 20 of the absolute pressure which obtains in said mixture passage in the vicinity of the fuel nozzle. This control member will be referred to hereinafter as the "manometric control member" to facilitate the description. In the preferred 25 embodiment, a second regulating device influencing the discharge of fuel delivered by the fuel nozzle is controlled by the throttle. The manometric control member is arranged in such manner as to provide automatic functioning of the 30 carburetor; that is to say, in such manner that the carburetor will deliver to the motor a mixture of the correct composition under all conditions of operation, and, when applied to an aircraft carburetor, is furthermore arranged in such 35 manner as to provide an altimetric correction, that is to say in such manner as to modify the discharge of fuel in the degree required by variations in altitude.

It is known that the composition of the combustible mixture supplied to an internal combustion engine need not be an absolutely fixed one, but that this composition may on the contrary vary within certain limits. As a general rule, if the richness of the mixture is increased, 40 the motor is enabled to develop greater power, but the specific consumption is higher in such case. It is of advantage, chiefly in aviation carburetors, to provide means for modifying the richness of the mixture delivered, so as either to 45 get maximum engine power or to diminish the specific consumption. In general, this modification of the richness is made at the will of the pilot.

The present invention has for its object an 50 arrangement permitting the richness of the combustible mixture to be varied in carburetors of the type described in said Belgian patent.

According to the present invention, the influence 55 of the manometric control member on the discharge of fuel may be varied by a supple-

mental adjusting member. This adjusting member will generally be manually controlled, but it will obviously be possible to control it automatically the same as other organs of the carburetor.

5

The description which follows, taken in connection with the appended drawing, will give, by way of example, a ready understanding of several ways of realizing the invention.

Figures 1 to 3 represent schematically, in 10 longitudinal section, several forms of the invention.

The carburetor shown in Figure 1 comprises a mixture passage 1 having an air inlet 2 and a mixture outlet 3 connected to the motor. The 15 effective cross section of the mixture passage 1 is controlled by a throttle 4 actuated by means of lever 5 and rod 6.

A fuel pressure regulator designated as a whole by the numeral 44 includes a fuel chamber 10 20 supplied with fuel under pressure through the conduit 11 and the orifice 14. The fuel chamber 10 is closed by a flexible membrane 12 connected to a movable valve member 13 controlling the inflow of fuel to the fuel chamber 10 through the 25 orifice 14, the arrangement being such that any increase in pressure within the fuel chamber 10 or any decrease in pressure within the adjoining chamber 45 tends to move membrane 12 upward- 30 ly and close the valve 13, 14.

A calibrated orifice 43 is supplied with liquid fuel by the fuel chamber 10 of the pressure regulator 44. The second chamber 45 separated from the fuel chamber 10 by membrane 12 communicates freely with the air inlet 2 of the carburetor 35 through passages 46 and 47 in such manner that the upper surface of the membrane 12 is subjected to the air supply pressure of the carburetor. Calibrated orifice 43 is controlled by a tapered needle 48 the shaft 49 of which passing 40 through guide 27 is controlled by the throttle valve 4 through the intermediary of the arm 28 of lever 5, link 29 and lever 30 turning about the axis 21.

Calibrated orifice 43 opens into an intermediate chamber 50 communicating with the venturi 8 through a calibrated passage formed by the annular space between the orifice 51 and shaft 49 of needle 48. The fuel outlet is formed by extremity 59 of calibrated orifice 51. The intermediate chamber 50 is also connected to the mixture passage 1 through a bypass 154 controlled by valve 155. The valve 155 may be operated by means of a lever 156. The intermediate chamber 50 is in addition connected by a calibrated orifice 55 52 through passages 53 and 47 with the air inlet 55 of the carburetor.

An enclosed manometric capsule 55 has one end attached to a wall of chamber 56, which communicates with the venturi 8 through passage 57 60

opening into the venturi at a point 58 where the pressure is approximately the same as at the fuel nozzle 59. At its opposite end capsule 55 carries a cylindrical shaft 60 passing through 5 guide 61 and having a tapered portion 54 controlling the effective cross section of orifice 52.

The fuel delivered through calibrated orifice 43, before reaching the fuel outlet 59, is emulsified with the air supplied from the air inlet 2 to 10 the intermediate chamber 50 (depression chamber) through passages 47 and 53 and orifice 52.

Under normal operating conditions the valve 155 is opened in such a manner that part of the emulsion is delivered to the mixing chamber 8 15 through bypass 154.

The depression which is transmitted to the intermediate chamber 50 through fuel outlet 59 and the bypass 154 is lowered by the air entering through orifice 52, and the depression transmitted 20 to the intermediate chamber 50 depends on the effective cross section of orifice 52 which is regulated by the tapered valve member 54. This cross section depends on the elongation of the capsule 25 55 and this elongation in turn depends on the absolute pressure existing in the mixing chamber 8 and in chamber 56. The profiles of member 54 and of needle 48 are designed to produce automatic functioning and altitudinal correction, so that the carburetor will deliver a correct mixture under all working conditions and altitudes. 30

If valve 155 is closed by operating lever 156, the cross section available to the emulsified fuel by intermediate chamber 50 to the mixing chamber 8 becomes reduced and consequently the depression transmitted to the intermediate chamber 35 50 is weaker. Orifice 43, which supplies fuel to the intermediate chamber 50, is thereby subjected to a weaker depression. Its output diminishes and the mixture delivered by the carburetor becomes leaner.

The carburetor shown in Figure 2 differs from the carburetor shown in Figure 1 in that the bypass 154 is omitted. In addition the intermediate chamber 50 is connected to passage 47 leading 45 to the carburetor air inlet 2 both through orifice 52, the section of which is regulated by tapered valve member 54, and through bypass 157 controlled by valve 158. Lever 159 permits the operation of valve 158. Under normal operating conditions valve 158 is closed, but if one opens the valve by means of lever 159 the intermediate chamber 50 receives additional emulsifying air through bypass 157 with the result that the depression transmitted to the intermediate chamber 50 is diminished and the final mixture supplied by the mixture is leaner.

The carburetor shown in Figure 3, showing the application of the invention to the carburetor shown in Figure 5 of the Belgian patent, differs 60 from the carburetor shown in Figure 1 only in the arrangements which regulate the depression transmitted to the intermediate chamber 50. In the carburetor shown in Figure 3 the intermediate chamber 50 is connected by a restricted passage 62 with compartment 63. Compartment 63 connects in turn with the carburetor air inlet through calibrated orifice 64 and passages 53 and 47. Compartment 63 connects in addition with chamber 65 through calibrated orifice 66. Chamber 65 65 communicates freely through passage 166 with venturi 8 at a point 67 where the pressure closely approximates that at the fuel outlet 59. In chamber 65 is located an enclosed manometric capsule 68 carrying a profiled needle 69 which controls calibrated orifice 66.

The liquid fuel supplied by orifice 43 is emulsified anterior to its outlet at 59 into the mixing chamber by air supplied to the intermediate chamber 50 by orifice 62, chamber 63, orifice 64 and passages 53 and 47, which terminate in air inlet 2. Orifice 62 may have a relatively large section since its purpose is simply to create a slight difference in pressure between chamber 63 and chamber 50 in order that the fuel coming from chamber 50 can reach chamber 63, chamber 65 and venturi 8 after having passed through orifice 66.

Instead of providing a bypass connecting intermediate chamber 50 to venturi 8, obviously a bypass connecting chambers 65 and 63 might be provided.

Bypass 154 could similarly be replaced by a bypass connecting chamber 63 to passage 47 and controlled by a valve, this bypass being similar to bypass 157 shown in Figure 2.

I claim:

1. In a carburetor, an induction passage, a throttle controlling the same, a fuel conduit discharging into said induction passage posterior to the throttle, a fuel reservoir supplying liquid fuel to said fuel conduit, a throttle controlled variable restriction in the fuel conduit, and means for bleeding air into said fuel conduit comprising an air passage connecting the induction passage with the fuel conduit posterior to the variable restriction, a manually operable valve in said air passage for varying the effective cross-section thereof, a second air passage connecting the induction passage with the fuel conduit posterior to the variable restriction, a manometric capsule subjected to pressures in the induction passage and yieldable in response to variations in said pressures, and a valve connected to said capsule to be operated thereby for varying the effective cross-section of said second air passage.

2. In a carburetor, an induction passage, a throttle controlling the same, a fuel conduit discharging into said induction passage in a region of depression created by the restricting effect of said throttle, a fuel reservoir supplying fuel to said conduit, a throttle controlled variable restriction in said conduit, and means for varying the suction in said fuel conduit comprising two air passages connecting said induction passage with the fuel conduit posterior to said variable restriction for bleeding air thereinto, and independently operable manual means and means including a manometric capsule yieldingly responsive to the pressures in the induction passage for varying the air bleeding effectiveness of said air passages.

3. In a charge forming device, an induction passage, a throttle controlling the same, a fuel conduit discharging into said induction passage posterior to the throttle, a throttle controlled variable restriction in said conduit, a variable pressure chamber in the fuel conduit posterior to said restriction, and means for varying the pressure in said variable pressure chamber comprising two passages connecting the induction passage and the variable pressure chamber, at least one of said passages bleeding air into said chamber, means including a manometric capsule yieldingly responsive to variations in the pressure in the induction passage for varying the effectiveness of said air bleed passage, and manually operable means for varying the cross-sectional area of the other of said passages.
